WORK CONVEYER AND INVERTER

Kenneth Carlyle Butterfield, Grand Rapids,
Mich., assignor to General Motors Corporation,
Detroit, Mich., a corporation of Delaware

Application October 2, 1940, Serial No. 359,403

3 Claims. (Cl. 214—1)

This invention relates to material handling apparatus. In modern mass production, it is desirable to handle materials to and from the metal stamping presses with as much expedition and economy as is possible.

The present apparatus is an apparatus which is arranged to be rolled up at the side of a press for the purpose of receiving stampings from the press and for conveying the work away from the press and inverting the same and lifting the work to a position where it may be handled by men or may be taken up by some other conveying apparatus.

In the drawings:

Fig. 1 is a side elevation of the apparatus, some 15 of the parts being in section.

Fig. 2 is a plan view of the same.

Fig. 3 is a view of the press and some of the adjacent parts of the apparatus showing how the press trips some of the control valves.

Fig. 4 is a fragmentary plan view of the apparatus, similar to Fig. 2, but showing more of the press and showing the work ejector.

Fig. 5 is a longitudinal section of the apparatus showing the work lifting arm raised.

The apparatus is carried on a frame 1 which, in turn, is mounted upon small wheels or casters 2. This permits the apparatus to be wheeled around from place to place where it may be desirable to use it. On one end of the carriage—the end which is to be next to the press—there is an inclined way with rollers 3 to facilitate the work sliding down into a pit 4.

The work is released from the dies by means of a suitable knock-out 5 in the center of the female die. Any other form of ejector, such as knock-out pins, may be used. When the work is released, the upper die or ram 6 of the press, by means of a cam 7 on the side of the ram, trips a lever 8 which operates a Ross valve 9 to send the fluid through line 10 to cylinder 11 to operate piston 12 and thereby push the thrust rod 13 to the left, causing the work to be pushed out between the dies, as shown in the dotted lines of Fig. 3. It is pushed onto the rollers 3 and drops down into the pit 4, as shown by the dotted lines of Fig. 1.

The weight of the work swings the lever 14 from the position shown in the dotted lines to the position shown in the full lines (Fig. 1). This operates the fluid valve 15 and causes air to pass through line 16 to the right hand end of cylinder 11. This forces piston 18 to the left and this, in turn, thrusts the push rod 19 to the left, pushing the work over to the left hand 55

side of the pit, as shown at W in Fig. 1. The ram is rising from the position shown in the full lines in Fig. 3 to the position of the cam 20 (shown in the dotted lines of Fig. 3) trips the trip 21 which 5 operates the Ross valve 22 to send air through line 23 to the left of the cylinder 24 which causes piston 25 (Fig. 5) to travel to the right in cylinder 24. Piston rod 26 operates bell crank lever 27 which forms a lifting arm 28. This lifts the 10 work out of the pit, as clearly shown in the dotted and full line showings of Fig. 5. The work is now inverted and upon the table 29 where it may be handled by workmen, or it may be picked up by some other conveying apparatus.

I claim:

1. In a work conveyer and inverter, the combination of a frame having a slideway with a pit having an inclined wall at the side of the pit remote from the end of the slideway, means the 20 operation of which is initiated by the work for pushing a flat piece of work from the side of the pit at the end of the slideway to the other inclined side of the pit and means for lifting the work out of the pit and sliding the same up 25 along the inclined wall of the pit to thereby invert the same, comprising a swinging lever and means for controlling said swinging lever comprising a valve arranged to be tripped at the proper time by a moving member on the machine 30 from which the work is taken.

2. In a work conveyer and inverter, the combination of a frame having a slideway with a pit having an inclined wall at the side of the pit remote from the end of the slideway, means for 35 pushing a flat piece of work from the side of the pit at the end of the slideway to the other inclined side of the pit and means for lifting the work out of the pit and sliding the same up along the inclined wall of the pit to thereby invert the same, comprising a swinging lever, the said pit 40 provided with a trip lever, a fluid line, a valve for controlling the fluid line, a fluid cylinder and piston connected to said fluid line provided with a piston rod which affords the means for pushing the work from one side of the pit to the other, the said trip lever being tripped by the work as it falls into the pit.

3. In a work conveyer and inverter, the combination of a frame having a slideway with a pit 50 having an inclined wall at the side of the pit remote from the end of the slideway, means for pushing a flat piece of work from the side of the pit at the end of the slideway to the other inclined side of the pit, means for lifting the work out of the pit and sliding the same up along the

inclined wall of the pit to thereby invert the same, comprising a swinging lever, a fluid line, means for controlling said swinging lever including a valve in said fluid line arranged to be tripped at the proper time by a moving member on the machine from which the work is conveyed, the said pit provided with a trip lever and

another valve for controlling the fluid line, a fluid cylinder and piston connected to said fluid line provided with a piston rod which affords the means for pushing the work from one side of the pit to the other, the said trip lever being tripped by the work as it falls into the pit.

KENNETH CARLYLE BUTTERFIELD.
